BED DAVENPORT

William E. Wunderlich, Muncie, Ind., assignor to
 The Moore Company, Muncie, Ind., a corpora-
 tion of Indiana

Application November 26, 1934, Serial No. 754,692

1 Claim. (Cl. 5—47)

My invention relates to bed davenport, and it is my object to produce an article of this kind in which the operating mechanism will be of a simple and economical construction and especially adapted for use in bed davenport where the seat and back frames are of wood.

In carrying out my invention I provide at each end of the bed davenport a pair of pivotally interconnected brackets, one of which is adapted for attachment to the seat-frame and the other of which is adapted for attachment to the back-frame. Between these two brackets I provide a slotted link for the purpose of holding them, and the frames to which they are respectively attached, in the proper angular relationship when the structure is to be used as a davenport. One of the two brackets at each end of the bed davenport is connected by two non-parallel links to a mounting member adapted to be secured to the stationary frame or base of the bed davenport.

The accompanying drawings illustrate my invention: Fig. 1 is a vertical transverse section through a bed davenport, on the line 1—1 of Fig. 6, the full line showing indicating the position of the parts when the bed davenport is adjusted to serve as a bed; Figs. 2 and 3 are fragmental views similar to Fig. 1, but showing in Fig. 2 an intermediate position of adjustment and in Fig. 3 the adjustment to the davenport position; Fig. 4 is a view similar to Fig. 1, but showing the structure adjusted to serve as a davenport; Fig. 5 is a section on the line 5—5 of Fig. 4; and Fig. 6 is a top plan view of the structure adjusted to serve as a bed.

In a general way, the invention of this application resembles that of my prior Patent No. 2,028,426, granted January 21, 1936, the chief difference between this application and the prior one being that the device of this application is primarily adapted for use in structures where the seat and back frames are wood rather than of steel, as in my prior patent.

The stationary part of my bed davenport comprises end frames 10 interconnected by front and rear rails 11 and 12, and shaped to form the arms of the davenport. A panel 13 may extend between the side rails 11 and 12 at the bottom thereof to provide with the side rails a box adapted to contain bedding.

An article of the type with which this application is concerned includes relatively movable seat and back frames. The seat-frame 14 includes end members 15 and the back-frame 16 includes end members 17. Conveniently, the two end members 15 and 17 at each end of the bed daven-

port are co-planar with each other and with a cross member 18 on the stationary frame or base.

The mechanism employed to interconnect the seat and back frames at each end of the davenport includes two brackets 20 and 21, conveniently of sheet-metal and adapted respectively for attachment to the seat-frame and back-frame. The two brackets 20 and 21 are provided with integral inwardly extending arms 22 and 23 respectively which are pivotally interconnected, as by means of a bolt or rivet 24. Preferably, each of the brackets 20 and 21 is located against the inside face of its associated end member and is secured thereto as by means of screws 25. Each bracket has an ear 26 which is bent to overlie the upper surface of the associated end member to which it may be secured by a screw 27. Each of the brackets 20 and 21 may also be provided at its inner edge with an outwardly extending ear 28 adapted to engage the inner end of the end member 15 or 17 and to be secured thereto by screws 28'. (See Fig. 6.)

Pivoted to the inner face of each bracket 21 on the back-frame I provide a longitudinally slotted link 30 the slot in which receives a pin 31 secured to the associated bracket 20. Near the free end of the link 30, its slot is provided with an upward extension 33 into which the pin 31 may enter. When the pin 31 lies within the slot-extension 33, the seat-frame and back-frame are held in the relative angular relation shown in Figs. 2, 3, and 4; but upon raising the free end of the link 30 to free the pin 31 from the slot-extension 33, the seat-frame and back-frame may be moved into substantially co-planar relationship.

To each of the brackets 21 there are pivotally connected two supporting links 40 and 41, the opposite ends of such links being independently pivoted in spaced relation to a mounting member 42, such mounting members 42 being attached to the cross members 18 of the base of the bed davenport. The links 40 and 41 are of such respective lengths, and their points of pivotal connection to the bracket 21 and the mounting member 42 are such that they guide the back-frame 17 for movement between the generally upright position shown in Fig. 4 and the horizontal position shown in Fig. 1. Conveniently, the ear 26 of the bracket 21 is provided with a projection which extends downwardly along the outer face of the associated end member 17 and to which the upper end of the link 40 is pivotally connected; while the upper end of the link 41 is connected to the bracket 21 by the pivot bolt or pin 24. The

upper end of the link 41 is offset inwardly to bring it into association with the arms 22 and 23.

It will be noted that when the back is in the upright position the lower end of the back-frame 17 is near the rear of the base, while in the horizontal position it is near the longitudinal center line of the base. The precise amount of inward movement of the lower end of the back-frame 17, as that frame moves from its vertical to its horizontal position, will depend largely upon the relative widths of the seat-frame and back-frame, the object being to have the seat-frame and back-frame overhang the sides of the base by approximately equal distances when the structure is adjusted to provide a bed.

When the structure is to be used as a davenport, the parts occupy the positions shown in Figs. 3, 4, and 5. In this condition, the pin 31 on each bracket 20 is received in the slot-extension 33 of the associated link 30, and the back-frame 17 and seat-frame 16 are thereby supported in fixed relative angular position, the force of gravity acting upon the link 30 serving to hold it downward and thus to maintain the engagement between the pin 31 and the slot-extension 33. The links 40 and 41 occupy nearly vertical positions and thus serve as struts supporting the rear side of the seat-frame 14, the front side of the seat-frame being supported by the front rail 30 11 of the base on which it rests.

When it is desired to convert the davenport into a bed, the front edge of the seat-frame 14 is raised, thus elevating the seat-frame and lowering the back-frame. This movement is continued until the back-frame engages the rear longitudinal rail 12 of the base, as indicated in Fig. 1, the seat-frame then occupying the dotted-line position shown in Fig. 1. To complete the adjustment, the links 30 are raised to disengage the pins 31 from the slot-extensions 33, whereupon the seat-frame may be lowered to the full-line position shown in Fig. 1 where it again receives support from the front rail 11.

Conveniently, mechanism operable from the front of the davenport is provided for raising both links to disengage the pins 31 from the slot-extensions 33. This mechanism may, as in my co-pending application, take the form of a rock-shaft 50 which extends longitudinally of the seat-frame 14 near the rear edge thereof. At its ends, the shaft 50 is offset to provide cranks 51 which engage the lower surfaces of the links 30. At an intermediate point, the shaft 50 is provided with a third offset forming a crank 52 which is connected to an operating rod 53 that extends forwardly across the seat-frame 14 to have its front end slidably received in a suitable guide bracket

54. The operating rod 53 may be provided with a handle 55 of any convenient construction.

The normal positions of the cranks 51 are shown in Figs. 1, 2, 3, and 4. As is clear from Figs. 2 and 3, when the pin 31 is received in the slot-extension 33 of the link 30, the cranks 51 are out of engagement with the links, thus permitting the links to drop under the influence of gravity. When, with the seat-frame occupying the dotted-line position shown in Fig. 1, the operating rod 53 is moved forwardly, the cranks 51 will be raised to lift the free ends of the links 30, as indicated in dotted-lines in Fig. 2. This movement of the links frees the pin 31 from the slot-extension 33 and permits the seat-frame to be lowered. As the seat-frame is lowered, the lower surface of each link 30 forces the cranks 51 to assume their normal position; so that when the seat-frame is again raised the cranks will not prevent the links from dropping to engage the slot-extensions 33 with the pins 31.

The pivotally interconnected brackets 20 and 21 at each end of the davenport, together with their associated adjusting link 30, supporting links 40 and 41, and mounting member 42, form a unitary sub-assembly which, in practice, is manufactured complete as such, the seat and back frames of the davenport being later mounted in such sub-assembly. The ears 21 and 28 on the brackets 30 locate the seat and back frames in definite positions in the brackets, and the only part of the sub-assembly whose point of attachment to the wooden parts of the complete structure must be measured is the mounting member 42.

I claim as my invention:

In a bed davenport, a base, a seat frame having end members, a back frame having end members, a pair of brackets respectively associated with the end members of said seat and back frames at each end of such frames, each of said brackets being secured against the inner face of its associated end member, said brackets having integral arms approximately coplanar respectively with the brackets, said arms overlapping each other, one of said brackets being provided with an ear embracing one edge of the end member associated with that bracket, a mounting member attached to said base, a supporting link pivotally connected to said ear and to said mounting member, a second supporting link disposed outwardly beyond said end members and having its lower end pivotally attached to said mounting member and its upper end offset inwardly into association with said arms, and a pivot pin pivotally interconnecting said arms and said second supporting link.

WILLIAM E. WUNDERLICH.
